(57) **CLAIM**

The ornamental design for an earphone case and earphones as shown and described.

DESCRIPTION

FIG. 1 is a front elevational view of an earphone case and earphones showing my new design;

FIG. 2 is a perspective view showing the earphones placed inside the earphone case;

FIG. 3 is a front elevational view showing the earphone case alone, where the earphones are omitted for clearer illustration of the earphone case;

FIG. 4 is a rear elevational view of FIG. 3;

FIG. 5 is a left side view of FIG. 3;

FIG. 6 is a right side view of FIG. 3;

FIG. 7 is a top plan view of FIG. 3;

FIG. 8 is a bottom plan view of FIG. 3;

FIG. 9 is a front, bottom, right perspective view of FIG. 3;

FIG. 10 is a front, bottom, left perspective view of FIG. 3;

FIG. 11 is a rear, top, right perspective view of FIG. 3;

FIG. 12 is a front elevational view showing the pair of earphones, where the earphone case is omitted for clearer illustration of the pair of earphones;

FIG. 13 is a rear elevational view of FIG. 12;

FIG. 14 is a left side view of FIG. 12;

FIG. 15 is a right side view of FIG. 12; and,

FIG. 16 is a top plan view of FIG. 12.

The broken lines show portions of the earphone case and earphones that form no part of the claimed design.

1 Claim, 16 Drawing Sheets
